DESIGN FOR A RECEPTACLE FOR INFANT'S FOOD

Edward J. Wormley, New York, N. Y., assignor to George S. Ujlaki Company, New York, N. Y., a partnership composed of George S. Ujlaki and Marina Ujlaki

Application November 3, 1944, Serial No. 116,128

Term of patent 7 years

(Cl. D58—25)

To all whom it may concern:

Be it known that I, Edward J. Wormley, a citizen of the United States and a resident of New York, in the county of New York and State of New York, have invented a new, original, and ornamental Design for a Receptacle for Infant's Food, of which the following is a specification, reference being had to the accompanying drawing, forming part thereof.

Figure 1 is a front elevation of a receptacle for infant's food, showing my new design;

Fig. 2 is a side elevation;

Fig. 3 is a plan view;

Fig. 4 is a partial rear elevation.

I claim:

The ornamental design for a receptacle for infant's food, as shown.

EDWARD J. WORMLEY.
